UNITED STATES PATENT OFFICE.

THOMAS E. HUNT, OF BLUE ISLAND, ILLINOIS, ASSIGNOR, BY MESNE ASSIGNMENTS, TO QUAKER MANUFACTURING COMPANY, OF CHICAGO HEIGHTS, ILLINOIS, A CORPORATION.

WARM-AIR REGISTER.

SPECIFICATION forming part of Letters Patent No. 715,806, dated December 16, 1902.

Application filed February 26, 1902. Serial No. 95,731. (No model.)

To all whom it may concern:

Be it known that I, THOMAS E. HUNT, a citizen of the United States, residing in Blue Island, in the county of Cook and State of Illinois, have invented certain new and useful Improvements in Warm-Air Registers, of which the following is a specification.

The objects of the invention are to improve the construction and arrangement of the plates or castings constituting the front, the top, and the front side corners of the frame or support for a warm-air wall register box or casing; to improve the construction of the tin or sheet-metal body of the register box or casing and its attachment to the plates or casting of the box or casing frame; to improve the construction or joint at the bottom of the register box or casing for the ready reception of and a close fit around the warm-air-supply pipe or boot; to improve the construction and operation of the controlling damper or door for the passage of the warm air from the register, and to improve generally the construction of the various elements which enter into the formation of the register as a whole and the construction and operation of the register.

The invention consists in the features of construction and combinations of parts hereinafter described and claimed.

In the drawings, Figure 1 is a front elevation of the register; Fig. 2, a top plan view of the same; Fig. 3, a bottom plan view of the same; Fig. 4, an end elevation of the register; Fig. 5, a vertical cross-section of the register in place on a section of pipe; Fig. 6, an inner face view of the front plate or casting for the register; Fig. 7, an under face view of the top plate or casting for the register, one end being broken off; Fig. 8, a detail showing one of the front corners of the body of the register-casing with the attaching vertical corner post or support therefor; Fig. 9, a detail in elevation of one of the vertical front corner posts or supports; Fig. 10, a detail in cross-section of one of the corner posts or supports; Fig. 11, a horizontal cross-section of the register-walls, taken on line 11 of Fig. 5, with the front casing, the swinging

door or damper, and the grate removed, showing the convexity of the end plates of the body of the casing for giving a spring action to retain the controlling damper or door in an adjusted position; Fig. 12, an inner face view of one end of the register-body, showing a bow-spring for maintaining the controlling door or damper in an adjusted position; Fig. 13, a horizontal cross-section of the end shown in Fig. 12, showing the attachment of the retaining bow-spring for the door or damper; Fig. 14, a detail showing one corner of a door or damper having a trunnion or journal-pin for suspending the door or damper to swing from the trunnions or pins; Fig. 15, a plan view showing a wire grate in one form of construction; and Figs. 16 and 17, sectional detail views, enlarged, of the rear and front joint-sockets, respectively, at the bottom of the shell or casing.

The register is constructed with a front A, preferably of cast metal and of an oblong or square formation in elevation, as may be desired. This front plate or casting A has a lower solid plate a and an upper plate or bar a' and side plates or bars a^2 , surrounding an oblong opening A' , through which the warm air can flow from the register-box into the room in which the register is located when the controlling damper or door is in proper position. The lower front wall a and the upper front bar a' , forming a portion of the upper wall, are in different vertical planes, with the lower front plate farther projecting than the upper bar, as shown in Figs. 5 and 6, and a horizontal shoulder a^3 is formed on the inner face of the bar or wall a' , extending on each side to a vertical shoulder or ledge a^4 , from which ledge or shoulder a flange or rim a^5 extends rearwardly, joining at the top a flange or rim a^7 , extending rearwardly from the top bar of the front or casting, leaving the front or casting open at the bottom with a shoulder a^6 at the lower end of the ledge a^4 on each side. The complete front plate or casting A has a lower plate in a straight vertical plane with upwardly and rearwardly extending end bars or walls a^2 and an upper cross-bar in a rearward plane to the lower

plate, enabling the register to be set with its lower portion projecting from the vertical wall of the room. The flanges or rims form receivers for the end plates of the tin or sheet-metal body of the box or casing, and, as shown, on the inner face of the front plate, below the opening for the outflow of air, are lugs a^3 for supporting the front side or edge of a grate, forming an open partition below and a support for the door or damper controlling the flow or passage of the warm air from the register-box.

The top B of the register is also preferably constructed of cast metal and of an oblong formation, with perfectly square corners. This top plate or casting B has on its upper face a flange or rim B' , forming an oblong collar for the attachment of the riser or extension leading to the room above that in which the register is located, which rim or flange surrounds an opening B^2 , preferably of an oblong formation. The rear edge of the top plate or casting B has thereon a depending ledge or rib b , and at each end of this plate or casting, on the under face, is a ledge or rib b' . The rear ledge or rib has thereon in the arrangement shown three depending lugs b^2 , spaced equal distances apart, two of which are shown in Fig. 7, and each end ledge or rib has thereon in the arrangement shown a single depending lug b^2 , and extending out from each rear and end lug is a rest or shoulder b^3 , against which the upper edge of the outer tin or sheet-metal plate of the casing abuts when the parts of the register are assembled, while the lugs furnish a separation for spacing the outer and inner tin or sheet-metal walls of the body of the box or casing, so as to form a dead-air space between the two walls. At each outer corner on the under face of the top plate or casting B at the juncture of the rear and end flanges or ribs is a right-angle lug b^4 , extending out from which in right-angle relation to each other are rests or shoulders b^5 , making a square corner for the attachment of the walls of the body of the box or casing, the shoulders or rests b^5 being in line with the shoulders or rests b^3 of the depending lugs b' and b^2 at the rear and ends of the top plate or casting. At the forward terminus of each end flange or rib b' is a spacing-lug b^6 , extending out from which on one side is a shoulder or rest b^7 in alignment with the shoulders or rests b^3 and b^5 on each end of the top plate or casting for the abutting edge of the plate or wall of the body of the casing. The outer corners and the straight-line faces of the lugs, in conjunction with the shoulders or rests, furnish a support and contact for the edge of the outer tin or sheet-metal plate of the body, and a support and contact for the inner tin or sheet-metal plate of the body when used is furnished by the under face of the top plate or casting. At the front on the under face of the top plate or casting B, near each end, is a depending lug b^8 , the lower end of which comes to

an apex, leaving a space between the front face of each lug and the rear face of the front plate or casting of a width sufficient for the reception of the upper edge of the door or damper G, controlling the outflow of the warm air from the register.

At each exterior front corner of the register-box, within the rearwardly-extending flanges on the front plate, is a corner post or support C, (shown in Figs. 8, 9, and 10,) each post or support having a flat wide body or wing c and a flange or wing c' , standing in right-angle relation to the body or wing c and having an outward projection when the parts are assembled. The rear edge of the body or wing c has near its lower end a lug or projection c^2 and near its upper end a lug or projection c^3 , each lug or projection having therein a hole for the passage of fastening screws or rivets. The upper end of the post or support C has therein a circular depression c^1 in the form shown in Figs. 8 and 9, which depression furnishes a support and bearing for a trunnion or journal-pin on the upper corner of the door or damper for controlling the outflow of the air from the register, and at the lower end of each post or support C is a projecting foot c^5 , and depending from the foot and the end of the post or support is a lug c^6 , in which is a hole for the passage of a fastening screw-bolt or rivet, and the foot of each standard when the parts are assembled passes beneath the shoulder a^6 at the lower end of the vertical ledge a^4 of the front plate or casting, giving a counter-support between the corner post or upright and the front plate or casting for maintaining the corner post or upright in a vertical position for the attachment of the front edge of the side walls of the body of the casing, leaving the lower end of the front plate or casting projecting in advance of each corner post or upright.

The construction shown has a double wall for the body of the casing of the register; but the casing can be formed of a single wall for the body. Each wall may be formed of a plate of tin or sheet metal bent into shape to have a wall at each end and a rear wall. The outer wall D at its lower end has an upturned edge d , and the inner wall at the lower edge has an upturned edge e with a turned-over edge e' , which overlaps the top of the turned edge d , forming a connection between the two walls or plates at the bottom on each end and the rear side by which the two walls will be held against springing apart laterally or separating, and at the same time a space d' is formed between the two upturned edges d and e , which space furnishes a socket for the entering of the top edge of the warm-air-supply pipe or foot for the attachment of the register as a whole to the warm-air pipe or foot, so as to have the attachment a close fit, preventing the escape of warm air upwardly into the space between the two walls or plates of the body, which space constitutes a dead-air

space and prevents a radiation of heat that might produce injurious effects or overheating of the walls in the use of the register. The socket is rendered tight and close-fitting.

5 when the edge of the warm-air-supply pipe or foot is entered thereinto by reason of the spring action or clasping effect produced by the upwardly-turned edges d and e of the plates and the connection of these edges one to the other at the top. The socket is exceedingly simple in construction and at the same time furnishes a close tight fit for the register to the warm-air-supply pipe or foot with an effectual safeguard against the escape of warm air into the dead-air space between the two walls of the body or to the outside of the register. The front edge of the ends of the walls or plates of the body of the casing terminate at the rear line of the outwardly-projecting flange or wing c' of each corner post or support, so that the main body is complete to the corner post or support, which would leave a space for the forward projection of the main plate or casting at the lower end. This space for the outer end walls is filled by a strip of tin or sheet metal D' , soldered, riveted, or otherwise attached at the turned ends to the end walls or plates and extending across the front of the register inside of the lower portion of the front plate or casting, and the ends of the inner wall or plate E are united by a strip E' , soldered, riveted, or otherwise attached to the end wall or plate with a space between the two front strips D' and E' . The front strip D' has an upwardly-turned edge d^2 with a turned-over interior edge d^3 of the strip D' , and at its top the strip E' has a turned-over edge e^3 , which overlaps the top edge of the strip D' , so that the two strips are engaged one with the other and locked against excessive spreading or separation, and when united a space d^4 is formed between the upturned edges d^2 and e^3 , corresponding to the space d' between the upturned edges d and e , for the purpose of entering the edge of the warm-air-supply pipe or foot, as described for the space d' , and operating in the same manner and for the same purpose.

An open partition or grate extends across the register from front to rear. This open partition or grate F in the construction shown in Figs. 1, 2, 3, and 5 is of cast metal having a front bar f , a rear bar f' , and end bars f^2 , with cross-bars f^3 from the front bar to the rear bar, leaving spaces between the cross-bars and the end bars. This open partition or grate F is located at the upper termination of the front vertical plate a of the front casting A and is of a width to extend across the space from front to rear of the register and, as shown, is supported at its front edge on the lugs a^8 and is held at its rear edge by pressure against the inner wall or plate of the body of the casing; but the grate could be otherwise supported so long as it furnished a guide and support for the door or damper controlling the outflow of air from the register.

The grate instead of being cast could be formed of wire woven together, so as to leave open spaces or meshes for the passage of the warm air, and a grate F' of wire is shown in Fig. 15, consisting of a frame f^4 , longitudinal wires f^5 , and cross-wires f^6 , forming a mesh with square openings; but the form of the mesh or spaces for the wire grate can be other than that shown without in any manner changing the operation of the grate.

A solid door or damper G is employed for directing the outflow of the warm air from the register. This door or damper, as shown in Figs. 1, 2, 3, and 5, has its upper end entered in the space between the lugs b^8 and the rear face of the top bar of the front or casting A , which space is wider at the bottom to permit of the necessary swing of the door. The lower end of the door, as shown, is inclined, so as to present a sharp front edge which rests on and bites against the upper face of the grate for the grate to furnish a support for the door or damper in its swinging movements, for which purpose the grate is on the arc of a circle corresponding to that described by the lower edge of the door or damper in swinging. The door instead of being held only between the depending lugs b^8 and the front bar a' can have at each corner a trunnion or journal-pin g , as shown in Fig. 14, to enter the bearing c^4 and suspend the door from the corner posts or uprights to permit of the swinging movement. The door can be swung completely forward to close the opening A' in the front or casting, or partly back, as shown by the dotted lines in Fig. 5, or completely back, so that its lower edge abuts against the rear wall of the body of the casing. It will thus be seen that by means of this swinging door or damper the direction of the outflow of the warm air can be regulated as may be desired for the outflow to pass wholly through the opening A' or wholly through the opening B^2 or be split or divided to pass into both openings. The door, near its lower edge in the construction shown, is provided with a handle or lug, by means of which it can be swung into any desired position. This knob or handle can be a solid knob or handle G' , as shown in Figs. 1 and 3, or it can be a handle G^2 in the shape of a coil of wire or other metal, the last form of handle being preferred, as it will not become too highly heated. The door should be held in its adjusted position; and for this purpose one or both of the end walls of the body of the casing can be curved inwardly to present a convex bearing-face which will engage the end or ends of the door and hold the door in an adjusted position, and end walls of this character are shown in Fig. 11. Instead of having the end walls furnish the frictional contact for holding the door or damper in an adjusted position springs can be employed for this purpose, as shown in Figs. 12 and 13, in which the spring H is of a curved or bow formation having at each end a tongue h to enter walls h' in the end wall of the body of the

casing, and the spring is of the requisite elasticity to furnish the necessary pressure for the frictional engagement to hold the door or damper and at the same time is of a nature 5 to give and take in the movements of the door or damper, by which it will be flattened at one end and raised at the other end, according to the direction of movement of the door or damper, and other means than the 10 convexity of the end wall or walls or a bow spring or springs can be employed for holding the door or damper in an adjusted position.

The outer and inner walls when a body with a double wall is used are arranged with the 15 two walls one within the other and interlocked at the lower end by the upturned edges, which form the socket-joint for the lower end of the body. The top plate is placed on the upper end of the two walls, with the spacing-20 lugs of the top plates entered between the walls, and the top plate is secured in place by rivets, screw-bolts, or otherwise passing through the middle lug at the rear side or edge of the plate and the lug at each end of 25 the plate. The corner posts or supports are inserted between the plates of the double walls at each front corner and secured in place by rivets, screw-bolts, or other means passing through the lugs of each corner-iron, 30 which lugs are entered into the space between the walls, with the edges of both the inner and outer walls flush against or abutting the outward-extending rib or flange of the corner-iron. The front strips D' and E' are 35 interlocked by their upturned and overturned edges and are secured by soldering or otherwise to their respective body-walls, and the front plate is then placed in position and secured by screw-bolts or other means passing 40 through the shoulder or rib a' of the front and through holes in the rib or flange c' of each corner-iron, completing the assembling of the register as a whole. The front can be removed when the register is to be placed in 45 the wall, and the register without the front can be placed in position and its lower end entered onto the end of the warm-air-supply pipe or the foot, and when in position the front can be replaced in position, completing the placement of the register in the side wall. The 50 projection of the lower portion of the register from the side wall gives an increased opening at the bottom, enabling the full capacity of the warm-air-supply pipe to be utilized in 55 the register. The corners of the casing at the bottom are square, enabling the end walls to be perfectly straight, giving an easier attachment for the warm-air-supply pipe or foot and rendering the attachment and connection 60 safer than with the use of rounded corners and irregular sides. The joint-socket at the lower end of the casing receives the end of the warm-air-supply pipe or boot, which can be entered into the socket-joint and will be clamped 65 therein and held without requiring any soldering or other securing means, and at the same time the space will be closed against the

passage of warm air to the outside of the casing. The swinging door or damper enables the outflow of air to be all directed through 70 the front opening or all directed through the top opening or divided for part of the air to flow through the front opening and part through the top opening, and these combined features add materially to the register and 75 give increased advantages therefor over registers of the usual construction.

What I regard as new, and desire to secure by Letters Patent, is—

1. In a warm-air register, the combination 80 of a frame comprising a front plate having an opening in its upper portion and having its lower or bottom portion projected beyond its top, a top plate having an opening surrounded by an upwardly-extending flange forming an 85 attaching-collar, corner posts or uprights for the front of the box or casing and a casing having end walls and a rear wall attached to the top plate and the corner-posts, substantially as described. 90

2. In a warm-air register, the combination 95 of a frame comprising a front plate having an opening in its upper portion and having its lower or bottom portion projected beyond its top, a top plate having an opening surrounded by an upwardly-extending flange forming an 100 attaching-collar, spacing-lugs depending from the top plate on its under side at its rear edge and its end edges, corner posts or uprights for the front of the box or casing and a casing 105 having double end walls and a double rear wall attached to the top plate and the corner-posts and spaced apart on the ends and rear by the spacing-lugs, substantially as described. 110

3. In a warm-air register, the combination 115 of a frame comprising a front plate having an opening in its upper portion and having its lower or bottom portion projected beyond its top, a top plate having an opening surrounded by an upwardly-extending flange forming an 120 attaching-collar and having spacing and attaching lugs depending from its under face at the ends and rear side, corner posts or uprights for the front of the box or casing having spacing and attaching lugs thereon and a casing having double end walls and a double rear wall attached to the top plate and the corner-posts by the attaching-lugs and spaced apart by the lugs, substantially as described. 125

4. In a warm-air register, the combination 130 of an outer wall and an inner wall, of a sheet-metal casing, each wall having its bottom edge inwardly and upwardly turned and one edge 125 entered into and interlocked with the other edge, leaving a tapered space between the two edges at the bottom of the casing forming a socket-joint for the reception and retention of the end of a warm-air-supply pipe or boot, and a front casing having an opening in its upper section projecting above the top plate, substantially as described. 135

5. In a warm-air register, the combination

of a flat top plate provided with an opening for the passage of warm air and having on its under face adjacent to its end and rear side edges depending spacing and attaching lugs, 5 and a sheet-metal casing consisting of an outer wall and an inner wall attached to and spaced apart by the lugs of the top plate, each wall having at its bottom an inwardly and upwardly turned edge interlocked one with the other between the walls and forming a joint-socket for the reception and retention of the end of a warm-air-supply pipe or boot, and a front casing having an opening in its upper section and projecting above the edge of the 15 top plate, substantially as described.

6. In a warm-air register, the combination of an inner and outer wall of a sheet-metal casing each wall having an inwardly and upwardly turned edge on its bottom with the 20 edges interlocked one with the other between the walls, an outer cross-strip at the front of the casing extending from end to end of the outer wall of the casing, and an inner cross-strip at the front of the casing extending 25 from end to end of the inner wall of the casing, each strip having an inwardly and upwardly turned edge at its bottom with the edges interlocked one with the other between the strips and the strips interlocked at the 30 top, the inwardly and upwardly turned bottom edges of the walls and strips forming a socket-joint around the bottom of the casing for the reception and retention of the end of a warm-air-supply pipe or boot, substantially 35 as described.

7. In a warm-air register, the combination of a front plate having an opening in its upper portion and having a projected lower portion below the opening, a flat top plate having 40 a central opening therein, a casing attached to the top plate, an open-work partition or support in the casing and having a plain upper face and an upward curvature from front to rear, and a door or damper 45 swinging at its upper edge from the front edge of the top plate and bearing at its lower edge on the upper face of the partition or support, substantially as described.

8. In a warm-air register, the combination 50 of an open front having a closed projected portion below the opening, an open flat top having on its under face at its rear and end edges depending lugs, a shell or casing attached at its upper end to the depending lugs 55 of the top plate, a support in the shell or casing, and a swinging door or damper in the shell or casing contacting with the support for directing the outflow of warm air from the register, substantially as described.

9. In a warm-air register, the combination 60 of an open front having a closed projected portion below the opening, an open flat top having on its under face at its rear and end edges depending lugs, a shell or casing attached at its upper end to the depending lugs 65 of the top plate, a support in the shell or casing, a swinging door or damper operating in the shell or casing having its lower edge contacting with the support for directing the outflow of warm air from the register, and means 70 for holding the door in an adjusted swung position, substantially as described.

10. In a warm-air register, the combination 75 of an open front having a closed projected portion below the opening, an open flat top contacting with the open front having on its under face at its rear and end edges depending lugs, front corner posts or standards having attaching lugs or ears, a shell or casing attached at its upper end to the depending 80 lugs of the top plate and at its forward side to the corner posts or standards, a transversely-extending support in the shell or casing, and a swinging door or damper operating in the shell or casing above the support for directing 85 the outflow of warm air from the register, substantially as described.

11. In a warm-air register, the combination 90 of a register box or casing having a front composed of a single plate with a delivery-opening for warm air in its upper portion and a closed projected lower portion below the opening and having a flat top with a delivery-opening for warm air therein, and a door or damper swinging from its top within the 95 box or casing to coöperate with both openings for controlling the outflow of warm air from the register and front opening, substantially as described.

12. In a warm-air register, the combination 100 of a register box or casing having a delivery-opening for warm air in its front and a delivery-opening for warm air in its top, a door or damper vertically suspended to swing back horizontally from its top within the box or 105 casing and coöperating with both openings for controlling the outflow of warm air from the register through either opening and having a beveled lower edge presenting a sharp corner, and a curved grate engaged by the 110 sharp corner of the lower edge of the door or damper for the bite of the corner on the support to hold the door or damper in an adjusted position, substantially as described.
